UNITED STATES PATENT OFFICE

153,088

DESIGN FOR A HANDSAW

William D. Scalf and Lyde W. Ramsey,
Barbourville, Ky.

Application May 3, 1948, Serial No. 146,146

Term of patent 14 years

(Cl. D93—4)

To all whom it may concern:

Be it known that we, Lyde W. Ramsey and William D. Scalf, citizens of the United States, residing at Barbourville, in the county of Knox and State of Kentucky, have invented a new, original, and ornamental Design for a Handsaw, of which the following is a specification, reference being had to the accompanying drawing, forming part thereof.

Figure 1 is a perspective view of a handsaw, showing the new design applied thereto;

Figure 2 is a side elevational view of the new design; and

Figure 3 is a sectional view, taken substantially upon the plane of the section line 3—3 of Figure 2, and showing a part of the design.

The essential features of the design reside in the portions shown in full lines.

We claim:

The ornamental design for a handsaw, as shown and described.

WILLIAM D. SCALF.
LYDE W. RAMSEY.
